UNITED STATES PATENT OFFICE.

HIRAM W. CAMP, OF TULSA, OKLAHOMA, ASSIGNOR TO DOHERTY RESEARCH COMPANY, OF NEW YORK, N. Y., A CORPORATION OF DELAWARE.

PROCESS AND APPARATUS FOR TREATING HYDROCARBON OILS.

Application filed November 29, 1922. Serial No. 604,086.

The present invention relates to a process and apparatus for treating hydrocarbon oils and, more particularly, to a process and apparatus for distilling higher boiling point hydrocarbons under pressure to obtain lower boiling point hydrocarbons.

In the pressure distillation and cracking of hydrocarbon oils, residues containing hydrocarbons of high carbon content and of 10 sticky, viscous and tarry properties are formed, together with some free carbon. These residues are formed principally adjacent the heating surface and cling to and readily form deposits on any surface with 15 which they come into contact. Owing to the sticky, adhesive nature of the residues their removal from the surfaces to which they cling is very difficult during distillation and upon continued heating they harden and cement the free carbon into a hard, 20 dense, coke-like mass firmly adhering to the surface on which it is formed. Pressure distillation is, therefore, largely limited to stills which have smooth heating surfaces and 25 which afford ready access for cleaning, as, for example, the common type of horizontal, cylindrical still. Stills of this type, however, afford a minimum of heating surface and all of this surface is so positioned 30 that carbon readily deposits upon it. These deposits rapidly bake to coke, thereby aggravating the formation of troublesome 35 coatings which interfere with the still operation.

An object of the present invention is to provide a still which affords a large heating area and a surface on which there is little tendency for residues to settle and bake.

Another object of the invention is to provide a process of distilling hydrocarbon oils in which the residues are readily and effectively removed during distillation.

A further object of the invention is to provide a still in which the heat transmitting walls are so arranged as not to receive the falling residues or settling.

A still further object of the invention is to provide a still and furnace therefor in which an effective transfer of heat to the body of oil in the still and an accurate control of the temperature are provided.

Another factor of pressure distillation having a bearing on the effectiveness of the cracking treatment is the separation of the low boiling products from the heavier hy-

drocarbons in the still vapors and the rapid removal of the lower boiling vapors from the still while holding back the heavier hydrocarbon products. If the low boiling products are permitted to return to the still, 60 they absorb heat for their re-evaporation and may, themselves, be further broken down into gaseous products and lost. If a large quantity of heavy hydrocarbons is permitted to pass with the lighter products 65 from the still to the condenser, their subsequent separation involves considerable further expense.

Accordingly, a further object of the invention is to provide an apparatus in which 70 the heavier products in the still vapors may be effectively separated from the lighter vapors and returned to the still.

A further object of the invention is to provide a process of distilling hydrocarbons 75 under pressure in which the heavier constituents of the vapors of distillation are effectively separated from the lighter vapors and returned to the still.

Among the other objects and features of 80 the invention are the provision of an unheated still bottom portion into which the heavier residues of distillation tend to settle, of a scraping device for stills adapted to scrape adhering residues from the still 85 walls in such a manner as to permit them to readily settle away from the heated portion of the still, of a residue draw-off means adapted to effectively clear the bottom portion of the still from settling and of an 90 improved charging and run-back arrangement for the condensed still vapors.

With these and other objects in view, the invention comprises the process and apparatus described and set forth in the following specification and claims.

The various features of the invention are illustrated in the accompanying drawings, in which:

Fig. 1 is a side view, partly in section, of 100 a distilling apparatus embodying a preferred form of the invention, and,

Fig. 2 is a cross section of a still forming a part of the apparatus of Fig. 1, taken on line 2-2 of Fig. 1.

In the present invention, the hydrocarbon oils to be treated or distilled are heated in a vertical still in such a manner that the lower or bottom portion of the oil is unheated. In the heated zone or portion of the still, the 110

2 still is entirely surrounded by the burning gases and hot products of combustion and the heat is transferred to the body of oil through the vertical walls of the still. The 5 inner surface of the still wall is maintained clean of adhering distillation residues by circumferentially traveling scraper blades arranged in substantially vertical planes and having their outer, scraping edges yielding- 10 ly pressed outwardly to contact with the still walls. The adherent residues removed from the still walls settle to the lower unheated portion of the still, in which there is no tendency for them to rapidly harden, and 15 are removed through a draw-off pipe. The heating zone or portion of the still is heated by a furnace in which the burning gases and products of combustion are caused to travel in an upward, helical path around the still 20 walls, thereby providing a long path of contact with the still walls and an efficient utilization or absorption of the heat of the furnace gases by the still walls.

The vapors formed in the still are collected 25 in the upper portion of the still and pass to a dephlegmator or vapor tower. In this tower the vapors contact with a circulating stream of cold condensate which is circulated successively in a circuit through the 30 tower and through a cooling means, as, for example, a water cooled coil. The excess of condensate produced by the condensation of a portion of the vapors is returned to the still, together with a supply of fresh oil for 35 treatment. The vapor tower is protected from uncontrolled cooling by means of suitable insulation and the chilling or condensing temperatures in the tower are controlled to hold back any desired portion of the vapors formed in the still. The condensate from the tower is returned to the still by a pipe separate from the vapor pipe, thereby avoiding any disturbance of the conditions 40 established in the tower.

45 Referring more particularly to the accompanying drawings, a body of oil 10 to be treated is contained in a vertical cylindrical still 12 extending through a furnace 14 and projecting below the bottom wall of the furnace. The portion of the still within the furnace is filled with oil to a level substantially even with the top of the furnace and the oil is heated through the vertical still 50 walls 16 from the surrounding furnace gases. The body of oil is maintained under sufficient pressure to obtain the proper cracking 55 temperature in the still, the vapors being collected under pressure in a vapor space 18 in the top portion of the still and withdrawn 60 through a vapor outlet pipe 20.

An adhering layer of heavy hydrocarbon residues tends to form on the inner surface of the still wall 16, either through the contact of particles of heavy residues of distillation 65 circulating from the inner portion of

the body of oil to the still walls or, more probably, by being formed by cracking in contact with the hot walls of the still. This adhering layer is removed by means of scraping blades 22 carried in circular paths 70 around the inner surface of the still walls on a frame 24 rotating on a vertical shaft 26 arranged axially in the still. The scraper blades 22 are arranged substantially vertically, or inclined slightly forwardly toward 75 their upper ends, as, for example, about 5° from the vertical, in order that the residues scraped from the still walls may fall freely from the blades and to increase the forces tending to free the scraped material from 80 the blades.

The blades are yieldingly pressed outwardly in such a manner as to force the outer cutting or scraping edges of the blades into intimate contact with the surface of the still 85 walls while permitting them to give inwardly upon striking an inwardly extending projection of the still walls and to push outwardly into any irregularities in the still walls. For this purpose the blades are slidably mounted on individual arms 28 extending radially outward from the shaft 26 and are individually forced into contact with the still wall by weighted levers 30 which are pivoted to upright rods 32 in such a position that the outer ends of the levers bear against the blades by the gravity action of weights on the inner ends of the levers. The blades are preferably mounted slidably on the end portions of the arms 28 by means of 90 cross bolts or pins 34 passing through slots 36 in the ends of the arms. The vertical rods 32 are mounted on the outer portions of the arms 28 and are attached at their upper ends to a supporting spider 40 mounted on 95 the shaft 26. The outer ends of the spider frame 40 are supported by guy wires 42 extending from the outer ends of the frame to a collar 44 clamped to the shaft 26 and diagonal braces 45 are connected between adjacent arms of the spider. The shaft 26 is supported on the bottom of the still by means of a thrust bearing 46 carried on a suitable tripod or bracket 48. The upper 100 end of the shaft extends through a packing gland in the top of the still into a gear housing 50 where it is connected by suitable gears 52 and 53 with a drive shaft 54.

The heavy residues gathered by the blades 22 or formed in the body of oil 10 settle 105 downwardly through the body of oil into a settling chamber 56 formed at the bottom below the furnace 14. As this portion of the still is unheated there is little or no tendency for the settling to harden on the 110 walls of the still or still bottom on which they remain as a soft or loose, adherent, sludge like mass. The still bottom slopes 115 downwardly toward a central outlet pipe or well 58 into which the settling may flow 120

from the sloping bottom and from which they may be withdrawn through an outflow pipe 60 and valve 62. As the settling accumulates on the still bottom adhere to the bottom with considerable persistency they frequently remain clinging to the still walls when the liquid is drawn out in a steady stream, as the flow may not be sufficient to sweep them free from the walls. The residual liquor is therefore drawn out intermittently in short, fast flowing spurts which shake the adhering substances from the still walls and bottom and sweep them into the outlet pipe. To insure the required flow during these outflow intervals, a pump 64 may be attached to the outlet pipe 60 to increase the rate of flow when necessary. The end of the shaft 26 is also preferably extended into the well 58 and provided with a helical or screw blade 66 which rotates with the shaft and stirs up the settling in the well and prevents them from caking or packing to a solid mass during the period of accumulation. The bottom of the well or outlet 58 is closed by a removable plate 68 which may be removed when the still is to be cleaned. The still bottom is also provided with separate manholes 70 and 71 for cleaning purposes. To avoid danger of fire by contact of the hot still residues with the atmosphere as they are released from the still, the outlet pipe 60 may be connected with a cooling coil, or mounted in the form of a coil, in a cooling box 72.

The portion of the still within the furnace 14 is heated throughout its surface by rapidly moving and uniformly distributed combustion gases in such a manner as to obtain a rapid transfer of heat from the furnace to the interior of the still without excessive local temperature gradients or local overheating. To this end the flames and hot products of combustion are caused to travel about the still in a helical path and in rapid movement over the outer surface of the still. The fuel is ignited in an ignition chamber or Dutch oven 74 at one side of the furnace, a jet of fluid fuel from a burner nozzle 76 being used in the embodiment illustrated in the drawings. From the Dutch oven or ignition chamber 74 the burning fuel passes through a refractory grating 76 into a distributing chamber 78 formed in the lower part of the furnace by a horizontal perforated partition 80. The hot gases are distributed about the still by the partition 80 and, upon passing upwardly through the partition, flow upwardly through a helical flue 82 formed by a helical partition 84 extending inwardly from the furnace wall to the still walls. The rapid turning movement of the hot gases serves to continually bring new portions of the furnace gases into contact with the still walls thus insuring a rapid and uniform absorption of heat from

the gases. From the upper portion of the furnace the waste products of combustion are exhausted through an outlet flue 86 to a stack 88. Through the above arrangement of still and furnace, the greater part of the area of the still is utilized for heating the oil and, through the rapid circulation of furnace gases over the outer surface of the still and the efficient scraping and stirring action on the inner surface of the still, a rapid uniform heating is obtained.

The vapors passing from the still through the vapor line 20 enter a vapor tower or dephlegmator 90 at a short distance above the bottom of the tower and pass upwardly through the tower alternately through central openings 92 in annular plates 94 and annular openings 96 between plates 98 and the walls of the dephlegmator. In passing upward past the plates 94 and 98 the vapors come into intimate contact with bodies of condensate which are maintained on the plates by upwardly extending flanges 99. The vapors also directly contact with condensate trickling downwardly from plate to plate and are thereby cooled to a temperature at which the higher boiling constituents of the vapors are condensed and absorbed into the body of cold circulating condensate. The vapors reaching the upper part of the tower are therefore enriched in the lighter constituents and deprived of the undesired heavier constituents. As referred to in detail hereinafter cold condensate is introduced into the tower in order to effect and control the condensation of the vapors therein. This condensate is preferably introduced into the tower at a short distance from the top so as to leave a few plates above its entrance on which any entrained particles of heavy condensates may be caught and removed from the vapors before the vapors leave the tower. From the top of the tower the purified vapors pass through an outlet pipe 100 and a pressure release valve 102 to a suitable condenser 104.

The liquid condensate in its downward flow through the tower is heated by contact with the hot still vapors and gives up any vapors which it may have absorbed or condensed in the upper part of the tower. By a proper control of the temperature of the down flowing condensate, it reaches the bottom of the tower substantially free of the light products desired in the low boiling product and is composed principally of constituents suitable for cracking in the still 12. From the bottom of the tower the condensate is drawn through an outlet pipe 106, valve 108 and suction line 110 to a circulating pump 112. The condensate is forced by the pump through a cooling coil 114 in a cooling box 116 in which it is cooled to a temperature suitable for its admission to the upper portion of the tower 90. From

the cooling coil the cooled condensate passes through a pipe 118 and valve 120 to the tower 90, entering the tower below a group of plates 121 in the upper part of the tower. A relief valve 122 is inserted between the suction pipe 110 and the discharge pipe 118 by which a portion of the cooled liquid may be returned to the pump inlet and recirculated through the cooling coil. By means of this valve, in connection with the valves 108 and 120, the rate of circulation of condensate through the tower and the temperatures within the tower may be accurately controlled to provide the proper separation of the heavier from the lighter constituents of the vapors. To avoid any disturbance of this control through uncontrolled transmission of heat through the walls of the tower, particularly when the tower is subject to wide variations in atmospheric conditions, the outer surface of the tower is covered with a layer of heat insulating material 124. Variations in temperature through the cross section of the tower are also minimized or eliminated by this insulation.

The condensation of vapors in the dephlegmating tower may be controlled also by means of a cooling liquid which is circulated through a coil 125 in the tower adjacent the plates 121. The cooling liquid may consist of the cold incoming oil to be treated or may be water or other suitable liquid. By means of the cooling circuit of condensate and the coil 125 the character of vapors leaving the top of the dephlegmating tower may be controlled at will.

The still is preferably operated as a batch still in a semicontinuous manner; that is, after a quantity of the oil has been distilled off and other portions of the oil withdrawn from the bottom of the still to remove carbon, tar and sludge, oil may be charged into the still to maintain the proper level in the still. The oil may also be charged continuously without danger of the oil level rising too high. The pump in oil is received through a supply pipe 126 and forced by means of a pump 128 through a pipe 130 into a reflux return pipe 132. When oil is circulated through the cooling coil 125 at the top of the dephlegmator the pipe 126 will be connected with said coil as will be readily understood.

The amount of oil which is used in the cooling circuit for the dephlegmating tower does not vary much and therefore a small portion of the condensate from the tower is used in the circuit after the circuit has once been made up. The condensate is very hot when it reaches the bottom of the dephlegmating tower and a portion of this hot condensate flows through the line 106 and through a valve 134 into the reflux line 132. A certain portion of the condensate which is used for the cooling circuit in the tower

is introduced into the cooling circuit through the valve 108. The fresh incoming oil from supply is mixed with the condensate passing through the line 132 and if the fresh oil is not being continuously charged, a valve 136 in the pipe 130 is closed. A connection is made between the pipes 118 and 106 by means of a valve 138 and pipe 140 by which condensate from the cooling circuit may be introduced into the reflux line 132 if desired.

By using the condensates of the dephlegmating tower as a cooling medium a comparatively accurate fractionation of the cracked vapors may be carried on at the same time that the cooled condensate is used for controlling the temperatures of the condensates in the dephlegmating tower. When for example, crude oil or fresh incoming oil is inserted into the dephlegmating tower, this oil contains a mixture of light and heavy vapor fractions which disturb the equilibrium set up by the dephlegmating tower. The cooled condensate however does not contain the light vapors and acts only as a cooling medium without interfering with the vapor fractionation.

The still is provided with a safety valve 139 of any suitable construction and is so supported that access may be readily had to its cleaning plate 68 and man hole 70. To this end the bottom of the still is supported on a foundation or supporting structure 142 of concrete or other suitable structural material and a tunnel 144 for placing a cart under the outlet 58 and a room for the pump 64 are provided in this supporting structure.

Having described the invention, what I claim and desire to secure by Letters Patent is:

1. The process of dephlegmating oil vapors in a dephlegmating zone which comprises circulating a cooling medium in a closed cycle through a cooling zone for said medium and in heat interchange with vapors in said dephlegmating zone and recirculating through the cooling zone a portion of the cold medium leaving said cooling zone.

2. A process of controlling the temperature gradient in a dephlegmator, comprising introducing hot vapors from a still at a point near the bottom of the dephlegmator, introducing a chilled condensate into the dephlegmator at a point below the top thereof, withdrawing condensate from the bottom of the dephlegmator and returning a portion thereof to the dephlegmator after first chilling the same, injecting the other portion of condensate into the still, reducing the flow of the chilled condensate to the dephlegmator by diverting a portion of the same into the still and mixing fresh hydrocarbons with the condensate flowing to the still.

3. A process of controlling the temperature gradient in a dephlegmator, comprising introducing hot vapors from a still at a point

- near the bottom of the dephlegmator, introducing a chilled condensate into the dephlegmator at a point below the top thereof, withdrawing condensate from the bottom of the dephlegmator and returning a portion thereof to the dephlegmator after first chilling the same, injecting the other portion of condensate into the still, reducing the flow of the chilled condensate to the 5 bottom of the dephlegmator by diverting a portion of the same into the still and further reducing the flow of chilled condensate to the dephlegmator by diverting a portion thereof into the stream of condensate flowing from the bottom of the dephlegmator.
4. In apparatus for distilling hydrocarbons, a still, a dephlegmator, a vapor pipe leading from the still to the dephlegmator, means for withdrawing condensate from the 10 bottom of the dephlegmator and diverting one portion thereof to a cooler and another portion to the still, means for controlling the flow of the condensate to the still and cooler, means for returning the cooled condensate to the dephlegmator, and means for diverting some of the cooled condensate into the condensate being withdrawn from the dephlegmator.
5. In apparatus for distilling hydrocarbons, a still, a dephlegmator, a vapor pipe leading from the still to the dephlegmator, means for withdrawing condensate from the bottom of the dephlegmator, and diverting one portion thereof to a cooler and another portion to the still, means for controlling the flow of the condensate to the still and cooler, means for returning the cooled condensate to the dephlegmator and means for diverting some of the cooled condensate away 30 from the dephlegmator into the still.
6. The process of cracking hydrocarbon oils which comprises heating oil in a still to produce vapors therefrom, passing said vapors to a dephlegmating zone to produce a reflux condensate, passing a stream of said 35 reflux condensate through a cooling zone, forcing cooled condensate into the upper portion of said dephlegmating zone to flow therethrough in heat interchange with said vapors, circulating a portion of said cold condensate in a closed cycle through said cooling zone and diverting a portion of the cooled condensate being passed to the dephlegmating zone.
7. In apparatus for distilling hydrocarbons, a still, a dephlegmator, a vapor pipe leading from the still to the dephlegmator, means for withdrawing condensate from the bottom of the dephlegmator, and diverting one portion thereof to a cooler and another portion to the still, means for controlling the flow of the condensate to the still and cooler, means for returning the cooled condensate to the dephlegmator and means for diverting some of the cooled condensate away 40 from the dephlegmator into the still and means for injecting fresh hydrocarbon into the still along with the condensate injected therein.
8. In an apparatus for treating petroleum oils, a still, a dephlegmator, means for conducting vapors from said still to said dephlegmator, means for passing reflux condensate from said dephlegmator to said still, a cooler for liquids, means for passing a portion of the condensate produced in said dephlegmator in a closed cycle through said cooler and said dephlegmator to produce cooling of said vapors and means for passing a portion of the cooled condensate leaving 45 said cooler back through said cooler without passing it through said dephlegmator.
9. The apparatus defined in claim 8 in which means independent of said last mentioned means is provided for decreasing the amount of cooled condensate passing from said cooler into said dephlegmator.

In testimony whereof I affix my signature.

HIRAM W. CAMP.
